UNITED STATES PATENT OFFICE.

WALTER SANDS, OF MINNEAPOLIS, MINNESOTA.

STEEL-WOOL HOLDER.

Application filed October 16, 1926. Serial No. 141,961.

My present invention has for its object to provide an extremely simple and highly efficient holder intended for general use but especially adapted for holding steel wool and for operating the same for abrasive, scouring, polishing and cleaning purposes.

Of the many uses for steel wool it is especially well adapted for cleaning kitchen aluminum ware but it is objectionable for the reason that it is so hard on the hands and the sharp, stiff ends thereof and loose particles cut into the fingers of the operator. This objection to the use of steel wool is particularly true of the coarser grades but they are desirable for the reason that they cut faster and are much cheaper than the finer grades.

By the use of the improved holder a ball or wad of steel wool may be securely held in such a position as to cover the respective portion of the holder so that the same may be used to press the steel wool to its work and at the same time prevent said holder from coming in contact with the articles to be cleaned or polished and hence marring or scratching the same.

The shape of the holder is such as to permit the steel wool to be easily rubbed on irregular surfaces in corners, as well as flat or concavo-convex surfaces.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a plan view of the improved holder;

Fig. 2 is a side elevation of the same;

Fig. 3 is a perspective view showing the jaws separated;

Fig. 4 is a transverse section taken on the line 4—4 of Fig. 2; and

Fig. 5 is a fragmentary view showing the jaws closed and holding a wad of steel wool.

The improved holder includes upper and lower jaws 6 and 7, each of which is formed from a single flat spring steel member in opposing relation. Integrally formed in the inner ends of the jaws 6 and 7 are U-shaped extensions 8 and 9, respectively, nested, the former in the latter, and affording a tang to which a handle 10 is applied.

The handle 10 has a central longitudinally

extended seat into which the nested jaw extensions 8 and 9 are tightly nested, and which seat in cross section follows the contour of said nested extensions and thereby positively prevents the same from turning in the handle. It will be noted that the handle 10 is flat on its top and bottom so that the same may be firmly held by the operator and will not turn in his hand. Nested concavo-convex lugs 9' are pressed from the transverse portions of the jaw extensions 8 and 9 and thereby securely hold said extensions against endwise movement, the one in respect to the other, and with the jaws 6 and 7 positively secured in definite relation in respect to each other.

The free end portion of the upper jaw 6 is curved laterally toward the lower jaw 7 and extended slightly forward thereof. Both jaws 6 and 7 are spring separated and the lower jaw 7 is extended laterally away from the upper jaw 6 and its free end portion is extended laterally inward toward said upper jaw to afford a wide tooth 11. This tooth 11, when the jaws 6 and 7 are open, is spaced a considerable distance from the upper jaw 6, as shown in Fig. 2. During the closing movement of the jaws 6 and 7 the tooth 11 moves into the upper jaw 6 and is laterally spaced therefrom, as shown in Fig. 5.

A sliding collar 12 is mounted on the jaws 6 and 7 and adapted to draw said jaws toward each other and close the same when slid forward thereon from its retracted position, as shown in Fig. 2. Said collar 12, when retracted as shown in Figs. 1 and 2, draws the jaws 6 and 7 at the extensions 8 and 9 tightly together. During the projecting movement of the collar 12 on the jaws 6 and 7, said jaws are closed and their body portions, between said collar 12 and the handle 10, are held tightly pressed together.

Pressed from the upper jaw 6 is an upstanding lug 13, and a co-operating wedge-like surface 14 is pressed from the top of the collar 12 and arranged to engage the lug 13 and frictionally hold the collar 12 when positioned to close the jaws 6 and 7. This wedge-like surface 14, acting on the lug 13, also tightly presses the bodies of the jaws 6 and 7 together.

In Fig. 5 is shown a wad or ball of steel wool 15 held by the holder. In applying the steel wool 15 to the holder a portion thereof is inserted between the open jaws 6 and 7

and said jaws closed thereon, as shown in Fig. 5, by projecting the collar 12. During the closing movement of the jaws 6 and 7 the peculiar shape of said jaws and the arrangement of the tooth 11 fold the steel wool 15 under the end portions of said jaws so that the same may be held to its work by a downward pressure while being rubbed over a surface to be cleaned or polished and 10 when in this position covers the respective portion of the holder to prevent the same from coming in contact with the article being cleaned.

The collar 12, when in any position on the 15 jaws 6 and 7, prevents the bodies of said jaws, between the collar 12 and handle 10, or their extensions from separating under pressure applied to the jaws, and thereby prevent the same from splitting the handle 20 10. By clamping the bodies of the jaws 6 and 7 lightly together when closed the holder is materially reinforced and made rigid so that the same will not bend under pressure applied to the holder. Furthermore, 25 when the collar 12 is projected and the bodies of the jaws 6 and 7 tightly pressed together, the projecting end portions of said jaws are relatively short and hence will not bend and release the steel wool 15 when 30 operating the same.

The nesting of the jaw extensions 8 and 9 and the collar 12 securely holds the jaws 6 and 7 against edgewise movement, the one upon the other. The nested lugs 9', as previously stated, hold the jaws 6 and 7 against

endwise movement in respect to each other so that the tooth 11 is always in a positive relation to the jaw 6 and thereby securely clamps the steel wool 15 in the jaws so that the same will not be detached therefrom during its operation.

What I claim is:

1. A holder of the kind described comprising a pair of normally open spring jaws, a handle applied to the jaws and holding the same in assembled relation, the free end portions of the jaws being inturned and arranged to move past each other during the closing movement of the jaws, a sliding collar on the jaws and movable into a position to close the jaws, and a lug on one of the jaws, said collar having an inclined surface arranged to engage said lug during a movement of the collar to close the jaws and press the same together under a variable pressure, and frictionally hold said collar where set.

2. A holder of the kind described comprising a pair of members having jaws at one end and having extensions at the other end that are channel-shaped in cross section and seated the one within the other, and a handle applied to said extensions and holding the same assembled.

3. The structure defined in claim 2 in which the extensions have interlocking elements that hold said extensions against endwise movement in respect to each other.

In testimony whereof I affix my signature,

WALTER SANDS.
